UNITED STATES PATENT OFFICE.

HARRY WARD LEONARD, OF BRONXVILLE, NEW YORK.

RESISTANCE UNIT.

938,671.

Specification of Letters Patent. Patented Nov. 2, 1909.

Application filed November 13, 1905. Serial No. 287,203.

To all whom it may concern:

Be it known that I, HARRY WARD LEONARD, a citizen of the United States, residing at Bronxville, in the county of Westchester 5 and State of New York, have invented certain new and useful Improvements in Resistance Units, of which the following is a full, clear, and exact specification.

My invention relates especially to electrical resistance units, such as might be advantageously used in the construction of rheostats, electric heaters and similar apparatus.

The principal object of my invention is to 15 improve the quality, reduce the cost and size, and produce a more commercial form of resistance units for many uses other than those heretofore known.

My invention is particularly well adapted 20 for the use of resistance ribbons and overcomes the difficulty that has been experienced in producing a substantial, tough, inexpensive form of apparatus, especially when the ampere capacity required for continuous duty is high, such for example as 25 fifty amperes and upward.

By my present invention, I can readily produce a resistance capable of carrying continuously many hundreds of amperes and 30 yet use for the purpose a ribbon so thin as to be so flexible by itself as to be of little commercial value unless properly supported, insulated and protected. I can use ribbons of nickel copper alloy having a thickness of 35 only one thousandth of an inch. Such resistance material is very perfect from technical considerations and the use of such thin ribbon is very inexpensive for a certain watt dissipating capacity. By varying the thickness 40 of the ribbon and by varying the width and length, a series of standard resistance units can be produced and these may be assembled by the user in any form, relation, and variety to secure the result desired by 45 him. A resistance can be expeditiously and economically produced which will have considerable strength and be of any desired ohms, number of steps, ampere capacity, shape and dimensions within desired limits.

50 My invention is capable of being embodied in a great variety of forms of construction and is therefore limited in its scope only as indicated by the appended claims.

My invention will be understood from the following description and the accompanying 55 drawings which show specific applications thereof.

Figure 1 is a side view of a resistance unit embodying my invention and comprising a reflexed ribbon; Fig. 2 is a section on 60 the line 2—2 of Fig. 1; Fig. 3 is a section on the line 3—3 of Fig. 1; Fig. 4 is a side view of a resistance unit which comprises a coil of wire; Fig. 5 is a section on line 5—5 of Fig. 4; Fig. 6 is a side view of a resistance 65 unit in which a reflexed wire is employed; Fig. 7 is a section on the line 7—7 of Fig. 6; Fig. 8 is a side view of a modification which employs a reflexed ribbon; and Fig. 9 is a section on line 9—9 of Fig. 8. 70

Referring to Figs. 1 to 3 there is shown a thin reflexed ribbon 1. Extending over the edges of the ribbon are two supports 2, 2' which are preferably trough like in form and of sheet iron. The ribbon is embedded 75 at its edges in this instance in vitreous enamel 3 which serves to insulate the ribbon from the supports 2, 2', and also securely and rigidly connects the parts. I prefer to attach each end of the conductor to a support and in the present structure the supports 2, 2' are shown as having extensions 4, 4' respectively which are bent at right angles. One end of the ribbon is secured by means of screws 5, nuts 6 and washers 7 to 80 the part 4 of the support 2 and the other end of the ribbon is connected by similar screws, nuts and washers to the part 4' of the support 2'. This not only produces a substantial and simple construction but affords a convenient means for securing electrical contact with the ribbon and also for 85 electrically uniting and coupling up any number of such units as desired. In this construction, the insulation is exposed to 90 the voltage represented by the drop in volts upon the ribbon due to the passage of the current but this drop will usually be very low. The sheet iron supports serve to considerably increase the radiating surface of 100 the circuit and aid in dissipating the heat.

Sometimes I use for the supports, brittle pieces such as pottery. Sometimes I use insulation which is itself non-adhesive such as mica. If the support itself provides the 105 necessary insulation, then separate insula-

tion will be unnecessary. The supports may extend more or less over the sides of the ribbon so as to protect it from injury. The supports may sometimes be perforated. It 5 will be seen that the length of the resistance unit may be made anything desired within reasonable limits.

By using the thinnest ribbon of high grade alloys, I obtain at a very moderate cost the 10 advantages of a resistance conductor of practically no temperature coefficient, non-oxidizing in ordinary practice, having a very large current capacity and very low and permanent resistance.

15 While I prefer to support the ribbon at its edge, I can when desirable, have it supported upon its side surface, when it would have the appearance in side view of Fig. 6. In some forms I may use a metallic braid 20 and if a ribbon is used I may perforate or slit it in order to vary its resistance.

While this invention at present seems most applicable to resistances of large current capacity, it may be applied to resistances 25 which are intended to carry only small current. For example, Figs. 4 and 5 show a construction in which a coil of wire 8 is used as the conductor. The wire is embedded at opposite sides of the coil in insulation 3, such 30 as vitreous enamel which also serves to rigidly unite the parts. The supports 9, 9' are here shown as having extensions 10 at the ends and provided with nuts and washers for coupling the units together mechanically, 35 and electrically using suitable insulation if electrical connection is not desired. The drawing shows one end of the wire 8 attached to one support at the end and the other end of the wire 8 attached to the other 40 support. The drawing shows insulation at the ends of the support which do not have electrical connection and also indicates how additional units, the extensions 10 of which are indicated, may be coupled up mechanically and electrically in bank, each alternate 45 terminal on each end being insulated and the other terminal being connected electrically.

Figs. 6 and 7 show a construction in which 50 a wire conductor 8 is also used but is reflexed instead of coiled. This is embedded in suitable insulation 11 which is inclosed by the supports 12, 12'. These supports have extensions 13, 13' to which the conductor is connected.

55 The supports may sometimes be held together by mechanical means so that an adhesive attaching material is not necessary. For example, binding wires may be wrapped around the outside of the unit. Such a construction is shown in Figs. 8 and 9 in which the construction is in general similar to that of Fig. 1, except an insulation 14 of mica, asbestos, porcelain, etc., might be used between the edges of the ribbon and the sup-

ports. The binding wires 15 serve to hold 65 the parts firmly together and these should be insulated from the supports 2, 2' if the ribbon is connected electrically to the supports.

In some cases it will be desirable to embed 70 the resistance unit in sand or some other medium having a high storage capacity for heat or having such properties as will still further protect the unit mechanically or electrically.

Having thus described my invention, I declare that what I claim as new and desire to secure by Letters Patent, is,—

1. The combination of a reflexed ribbon conductor, and two protective sheet metal 80 supports, the said ribbon being supported edgewise between said supports and the opposite terminals of said conductor being electrically connected to said supports respectively.

2. The combination of a resistive conductor, two supporting members therefor supporting said conductor between them, and means for insulating said members from each other and from said conductor and for 90 adhesively attaching the parts together, the opposite ends of said resistance being electrically connected to said two members respectively.

3. In a resistance unit, the combination of 95 a resistance, and supporting means therefor comprising sheet metal elements supporting said resistance between them and an adhesive coating of mineral insulating material for insulating the parts, the said elements being electrically connected together 100 by said resistance.

4. In a resistance unit, the combination of 105 a flexible metallic ribbon, two rigid supports therefor, means for adhesively attaching said supports to opposite edges of said ribbon respectively to form a rigid structure, and circuit terminals for said ribbon carried by said supports respectively.

5. In a resistance unit, the combination of 110 a resistance, two protecting and supporting members between which said resistance is held so as to be openly exposed to the free emission of heat by radiation and convection, and circuit terminals carried by said 115 members and to which the opposite ends of said resistance are connected respectively.

6. In a resistance unit, the combination of 120 two metal supporting members, a resistance between said members openly exposed to the free emission of heat by radiation and convection, means adhesively attaching said resistance to said members while insulating said members therefrom, and means for electrically connecting the two ends of said resistance with said members respectively.

7. In a resistance unit, the combination of 125 two trough-shaped members, a resistance be-

tween said members openly exposed to the free emission of heat by radiation and convection, means adhesively attaching said resistance to said members while insulating said members therefrom, and means for electrically connecting the two ends of said resistance with said members respectively.

In testimony whereof I affix my signature, in presence of two witnesses.

H. WARD LEONARD.
